UNITED STATES PATENT OFFICE.

GEORGE E. PRENTICE, OF NEW BRITAIN, CONNECTICUT.

GARMENT-CLASP.

1,075,725.

Specification of Letters Patent. Patented Oct. 14, 1913.

Application filed June 29, 1912. Serial No. 706,570.

To all whom it may concern:

Be it known that I, GEORGE E. PRENTICE, a citizen of the United States, residing at New Britain, in the county of Hartford and State of Connecticut, have invented certain new and useful Improvements in Garment-Clasps, of which the following is a specification.

My invention relates to improvements in garment clasps, and the object of my improvements is simplicity and economy in construction and convenience and efficiency in use.

In the accompanying drawing: Figure 1 is a front elevation of my improved clasp. Fig. 2 is a rear elevation of the same. Fig. 3 is a side elevation on an enlarged scale of the same. Fig. 4 is a sectional view on the line *x-x* of Fig. 1. Fig. 5 is a similar view of the same with the clamping members released from the clamping position. Fig. 6 is a plan view of the blank for the fixed clamping member. Fig. 7 is a similar view of the blank for the moving clamping member. Fig. 8 is a similar view of the blank for the clamping lever. Fig. 9 is a plan view of the moving clamping member complete. Fig. 10 is a sectional view on the line *y-y* of Fig. 1. Fig. 11 is a side elevation of a modification of the garment engaging members.

My garment cast off A comprises a fixed clamping member B, a moving clamping member C, and a clamping lever D, all made of sheet metal. The fixed clamping member B comprises a base plate 15 which is somewhat elongated, and has a bar 16 at the upper end suitable for receiving the loop of a webbing E, and at the lower end is provided with means for securing a button F, which latter is preferably of rubber, and intermediate the said ends there is a pair of laterally disposed ears 17 provided with pivot holes 18, and adjacent the upper end there is provided in the center of the body portion 19 a rectangular hole or diminutive slot 20, and the portion of the base plate 15 adjacent the said hole 20 is plane and suitable for a bearing surface for fingers 25 and 26 on the moving clamping member C.

The button F has a cylindrical body 21 and an enlarged base 22 and the means for securing the same to the base plate 15 comprises a flange 23 and a plurality of lugs 24 engaged with the said base 22 in an ordinary manner.

The moving clamping member C comprises an elongated strip provided at the upper end with a plurality of fingers referred to above, comprising a middle finger 25 and a pair of lateral spring fingers 26, and at the lower end with an eye 27 that is appreciably larger in diameter than that of the body portion 21 of the button F and intermediate the said ends is provided with an inclined body portion 28 suitable for being operatively engaged by the clamping lever D.

The fingers 25 and 26 are formed by a pair of longitudinal slits 29 in the blank and the upper ends of the lateral fingers formed thereby are cut away so that the lateral fingers 26 are shorter than the middle finger 25 and the free end 30 of the middle finger 25 projects upwardly beyond the lateral fingers 26. The said free end 30 of the middle finger 25 passes through the hole 20 in the base plate 15 suitably to engage with the rear side of the upper wall 31 thereof while the free ends 32 of the lateral fingers 26 are engaged with the front face of the lower wall 33. The free ends 30 and 32 are preferably suitably bent as shown to make flat-wise engagement with the said walls 31 and 33 in the manner described, the end 30 being in the form of a toe making engagement with the wall 31 by its front face and the ends 32 being each in the form of a shoe resting with the rear face on the wall 33. The bend in the middle finger 25 is in the form of a compound curve approximating a pair of right angle bends whereby the portion 34 that passes through the hole 20 is directed at approximately right angles to the base plate 15 and the length of the hole 20 is appreciably greater than the thickness of the material of the finger 25 whereby limited longitudinal movement will be permitted of the moving clamping member C relatively to the fixed clamping member B and with the toe 30 retained in engagement with the wall 31. The lateral spring fingers 26 tend to elevate the moving clamping member C and the toe 30 engaged with the wall 31 serves as a pivotal connection.

The fingers 25 and 26 are ribbed as shown and the ribs may extend along the inclined body portion 28, particularly the middle rib 35 which latter engages with a recess 36 in the end of the clamping lever D and serves as guiding and positioning means for the moving clamping member C, particularly

in the closing or clamping movement. The said inclined portion 28 is inclined relatively to the fingers 25 and 26 and the eye 27 suitably to be operatively engaged by the clamping arm 37 of the clamping lever D. The said clamping lever D is an elongated strip having a pair of laterally disposed trunnions 38 suitable for engaging with the pivotal holes 18, and has a right angle bend 5 adjacent the said trunnions 38, and the clamping arm 37 referred to on one end, which is relatively short, and an arm 39 at the other end that serves as a locking member for limiting the pivotal movement in the 10 clamping position and the extreme tip end 40 of which may be bent suitably to serve as a thumb piece for convenience in operating.

As described, the moving clamping member C has a limited longitudinal movement 20 relatively to the fixed clamping member B. The moving clamping member C is initially at the uppermost limit with the eye 27 held 25 clear of the button F by the resiliency of the lateral spring fingers 26 and the clamping lever D is turned outward, and as the clamping lever is turned to the clamping position the clamping arm 37 engages with the inclined portion 28, the recess 36 being engaged 30 with the rib 35 and serving to position the moving clamping member C laterally, as mentioned, so that the eye 27 will register with the button F, and as the movement is continued the moving clamping member C is forced backward and by reason 35 of the frictional engagement of the arm 37 with the inclined portion 28 the moving clamping member C is carried bodily along so that the top edge 41 of the eye 27 is 40 brought forcibly into abutment with the top edge 42 of the button F, and with the garment interposed therebetween, and a further continuation of the clamping movement of the clamping lever serves to bend the

moving clamping member C and appreciably 45 adds to the security of the hold on the garment. Accordingly, the top edge 41 of the eye 27 and the opened top edge 42 of the button F serve as clamping members proper and there is permitted considerable leeway 50 in the dimensions of the eye 27 and the button F. Accordingly, in some cases, the eye 27 and button F may be dispensed with and in lieu thereof a pair of overlapping jaws 55 may be provided as in the modification shown in Fig. 11 suitable for receiving the garment therebetween.

It is apparent that some changes from the specific construction herein disclosed may be made and therefore I do not wish to be understood as limiting myself to the precise form of construction shown and described, but desire the liberty to make such changes, in working my invention as may fairly come within the spirit and scope of the same as 65 claimed.

I claim as my invention:—

A cast off comprising a fixed member, a movable member, and a lever, the said lever pivotally mounted on the said fixed member, 70 and having one arm having sliding engagement by one end with the said movable member, and means for connecting the said fixed and movable members permitting of a pivotal and also a relatively longitudinal 75 movement and the said means comprising a flat bearing portion on one member provided with an elongated hole and a plurality of fingers on the other member, one of the said fingers passing through the said hole and the ends of the said fingers engaged 80 with the two sides of the said flat bearing portion.

GEORGE E. PRENTICE.
